1

This invention relates to knitted fabric and to a method of making the same.

The expression "fabric" is used herein in a generic sense to include not only fabric in the piece for subsequent cutting up and making into any appropriate articles, but also knitted articles for wear such, for instance, as various undergarments, outer garments, socks, and so on.

The object of the invention is to provide a novel knitted fabric having therein what may conveniently be termed raised eyelet effects adapted to impart to the fabric not only a bold and attractive appearance but also a pleasing feel.

The knitted fabric constituting this invention has at desired locations thereof small openings or eyelets produced by laterally spreading portions of yarn between and interlooping the same with adjacent knitted loops to form pelerine stitches, and these pelerine stitches are so linked with tuck loops that at the locations at which the openings or eyelets occur the surface of the fabric is raised.

The said tuck loops may be either directly interengaged or interlinked with the pelerine stitches providing the openings or eyelets or they may be slightly more remotely linked or coupled therewith by intermediate linking or coupling loops. In any event the disposition of the tuck loops may advantageously be such that the resulting knop-like raised puckered effects surround or frame the openings or eyelets, thereby producing well defined, bold and pleasing effects. The tuck loops may be linked or coupled with either or both sides of the pelerine stitches, the openings or eyelets being thereby opened out laterally to define yet more clearly the raised eyelet effects produced. Thus, expressed in other terms, a feature of the invention resides in the combination, at selected points in a knitted fabric, of pelerine stitches with tuck loops linked therewith. In this connection, the novel combined effects may conveniently be regarded, and for convenience will hereinafter be referred to, as "linked tuck-pelerine stitches."

Although it is within the scope of the invention to incorporate linked tuck-pelerine stitches in a so-called single-sided knitted fabric, by which is meant a fabric in which all of the knitted loops are drawn to one face only thereof, it is principally the intention to apply the invention to a double-sided fabric wherein, of the knitted loops, some are drawn to one face and others to the opposite face of the fabric.

Accordingly, the invention includes as a fea-

2

ture, the combination, in a double-sided knitted fabric, of pelerine stitches produced at desired locations by spreading bights or loops of yarn between and interlooping them with inwardly (or outwardly) facing knitted loops, with tuck loops which are associated with outwardly (or inwardly) facing knitted loops and are linked with the said pelerine stitches suchwise as to produce raised eyelet effects as hereinbefore described. Such a double-sided fabric may be either a rib knitted fabric of any desired rib combination, such as 2 x 2 or broad rib, or it may be a non-ribbed fabric which, however, has one or more purl stitch, i. e. links-links, portions or areas.

In any event, and whatever the class of knitted fabric concerned, the linked tuck-pelerine stitches may be distributed in any desired manner, according to requirements. For instance, the entire fabric, or at least one or more whole sections or areas of the same, may incorporate linked tuck-pelerine stitches disposed in regular, i. e. evenly spaced, series, both coursewise and walewise, suchwise as to produce "all-over" open-work having a cellular appearance. In cases where there are pre-arranged areas patterned by linked tuck-pelerine stitches, interspersed with non-patterned areas of the basic loop structure of the fabric, then the said patterned areas may be in the form of solid blocks, diamonds, zig-zags, and so on. Alternatively, the linked tuck-pelerine stitches may be appropriately dispersed suchwise as to produce various designs or jacquard patterns.

Thus, as will be appreciated, a knitted article produced in accordance with this invention, may include both portions patterned by the incorporation therein of the linked tuck-pelerine stitches and plain (non-patterned) portions or areas.

The invention also includes, as a further feature, the method of making the novel form of knitted fabric. In this connection the fabric is made on a knitting machine equipped with a set of pelerine instruments and having at least two knitting stations or feeds. The cycle or sequence of knitting operations necessary to produce the fabric is, broadly, as follows: At at least one knitting station or feed selected needles are caused to tuck, then at at least one further knitting station or feed not only are the accumulated tuck loops cleared and cast off the said needles, but selected pelerine instruments are also caused to engage and spread bights or loops of yarn between relevant loops on corresponding needles

and finally the previously selected pelerine instruments are operated, at a non-knitting station, to transfer the laterally spread pelerine bights or loops to adjoining needles. This cycle or sequence of knitting is repeated with, if desired, any appropriate variations in the selections of the needles and the pelerine instruments from cycle to cycle, until either the entire fabric or the patterned section or area to be produced is completed.

In the case of a two-feed knitting machine, the selection of needles to tuck would, of course, be effected at one knitting station or feed, and the tuck loops would be cleared and knocked over and a selection of the pelerine instruments for the purpose in view made at the other knitting station or feed prior to transference of spread pelerine bights or loops to desired needles at a subsequent transfer (non-knitting) station. Where, however, a multi-feeder knitting machine having, say, four or more feeds is employed, then selection of needles to tuck may take place at two or more succeeding knitting stations or feeds and knitting-off of the tuck loops and selection of the pelerine instruments to engage and spread bights or loops of yarn as aforesaid may take place at two or more following knitting stations or feeds prior to transference of the spread pelerine bights or loops to appropriate needles at a single transfer station. Any other desired and suitable division of the feeders may be adopted.

Rib or plain fabric incorporating the novel raised eyelet effects may conveniently be made on any suitable knitting machine having two needle beds (e. g. a circular machine of the cylinder and dial type) and with pelerine instruments arranged to work in either of said beds.

Rib or plain knitted fabrics, or fabrics incorporating links-links areas, may be made on a links-links machine fitted with a third bed for the pelerine instruments.

To enable the invention to be more clearly understood and readily carried into practical effect, specific examples of the improved knitted fabric, and a method making such fabrics on a multi-feeder circular knitting machine of the cylinder and dial type will now be described with reference to the accompanying drawings, wherein,

Figure 1 illustrates, on a greatly magnified scale, a fragmentary portion of 2 x 2 rib knitted fabric incorporating linked tuck-pelerine stitches,

Figure 2 is a fragmentary portion of single-sided knitted fabric made in accordance with the invention,

Figure 3 is a diagram illustrating a distribution of linked tuck-pelerine stitches in a portion of fabric providing an all-over pattern,

Figure 4 depicts one example of a knitted article, i. e. vest, patterned by linked tuck-pelerine stitches,

Figure 5 is a vertical sectional view of so much of the aforementioned machine as is necessary to illustrate the form of selector units and the jacks with which the machine is equipped for producing the improved fabric,

Figure 6 is a side view of one of the pelerine instruments in the machine and the corresponding jack, per se,

Figure 7 is an edge view of a pair of pelerine instruments and of the jack for controlling the same, and

Figures 8 and 8A each show, in developed form, a portion of the cam system of the machine at two knitting stations or feeds.

Like parts are designated by similar reference characters throughout the drawings.

Referring to the double-sided knitted fabric shown in Figure 1 it will be seen that this is a 2 x 2 rib fabric having spaced plain knitted panels A each comprising two consecutive outwardly facing wales P of plain loops a drawn to the front face of the fabric, and intervening rib knitted panels B each comprising two consecutive inwardly facing wales R of rib loops b drawn to the back of the fabric. Merely for the sake of convenience it will be assumed that this particular fabric is knitted on a two-needle bed circular knitting machine having, say, eight (or any appropriate larger number of multiple of four) knitting stations or feeds. Thus, at C,D,E,F, C,D,E,F, . . . are shown successively produced groups each of four courses knitted of four different yarns which, for clarity and to enable them to be readily distinguished from one another, are shown blacked in, unshaded, heavily shaded with horizontal lines and lightly shaded with vertical lines respectively. In practice, all of these separately fed yarns would usually be of the same colour, count and quality, although there is, of course, no limitation in this respect.

At each of pre-determined locations in some or all of the plain knitted panels A there are, in this example, two tuck loops c and d which are accumulated in two successive courses C and D and knocked together in the next course E so that they have drawn through them a pair of the plain loops a in the last mentioned course. That is to say, the tuck loops c and d extend laterally over two wales P. There are, on the other hand, at pre-determined locations in some or all of the rib knitted panels B pelerine stitches e providing openings or eyelets in the fabric. As will be seen, each pelerine stitch e is formed by collecting and laterally spreading, in three successive courses E, F and C, bights f, g, and h of yarns extending between pairs of rib loops b and knocking over this collection of spread bights so that they have drawn therethrough at h and are interlooped with a pair of the rib loops of the course C. The upper left-hand portion of each pelerine stitch e is linked with the right-hand ends of one pair of tuck loops c and d through the medium of linking loops i and j, whilst the lower right-hand portion of the same pelerine stitch is linked with the left-hand ends of a previously formed pair of such tuck loops c and d through linking loops k and l. In this respect there are, in this example, tuck loops linked with both sides of each pelerine stitch e, the resulting opening or eyelet being thereby opened out laterally in both directions clearly to define the novel effect. In other words, the tuck loops linked with each pelerine stitch are incorporated in the two plain knitted panels A immediately adjoining the opposite sides of the panel B incorporating the said pelerine stitch. Moreover, the pairs of tuck loops c and d linked with each pelerine stitch e are in staggered relation, the tuck loops coupled to the left-hand side of the said stitch being formed in the group of four courses immediately preceding the group of courses in which are formed the tuck loops coupled to the right-hand side of the stitch.

The linking of the tuck loops with the pelerine stitches tends to lift the face of the fabric and produce raised, puckered effects surrounding or framing the openings or eyelets, this being evidenced by the fact that certain of the plain loops a in the vicinity of the linked tuck-pelerine

stitches are larger than the remaining loops *a* in the outwardly facing wales *P*. In this connection it ought to be explained that Figure 1 is a correct, in contra-distinction to a theoretical, representation of the fabric, the figure being based on an enlarged photograph of the fabric as projected onto a screen; this accounts for the varying sizes and distortions of the loops. The well defined raised eyelet effects decorate the surface of the fabric in an attractive fashion, at the same time enhancing the feel of the fabric.

In Figure 2 is shown a single-sided, in contra-distinction to a ribbed, fabric consisting of a plain structure of knitted loops *m* all of which are drawn to one face only of the fabric. The fragmentary portion of fabric shown in this figure incorporates a linked tuck-pelerine stitch comprising a pelerine stitch *e* linked at opposite sides with pairs of tuck loops *c* and *d* in precisely the same way as shown in Figure 1—with the exception, of course, that it is loops *m* which are drawn through the tuck loops and the spread pelerine bights or loops *f*, *g* and *h*.

Figure 3, as previously mentioned, is a diagram illustrating a distribution of linked tuck-pelerine stitches providing an all-over jacquarded pattern. For simplicity in illustration, pelerine stitches *e* in this diagram are represented by circles, and tuck loops by small crosses. As will be seen, some of the pelerine stitches have tuck loops linked therewith at both sides thereof, whilst others are linked with tuck loops at one side only. The portion of fabric represented by the square in the diagram also incorporates, at pre-determined points, both separate pelerine stitches and also separate tuck stitches, that is to say pelerine and tuck stitches which are not linked together in accordance with this invention.

In Figure 4 is depicted, again in purely diagrammatic fashion, one typical knitted article for wear, viz. a vest, including an upper or bust portion *n* decorated by spaced vertical panels *o* patterned by desired distributions of linked tuck-pelerine stitches and having intervening non-patterned areas, and, below the waist *p*, a lower trunk portion *q* having an all-over jacquarded pattern of distributed linked tuck-pelerine stitches interspersed with separate pelerine and tuck stitches.

A circular knitting machine of the cylinder and dial type suitably equipped for carrying out this invention, and typical cycles of knitting on such a machine for producing a 2 x 2 rib fabric incorporating linked tuck-pelerine stitches, will now be described with reference to Figures 5-8A.

The particular machine now to be described, merely by way of example, is intended to have a minimum of four knitting stations or feeds such as those numbered 1, 2, 3 and 4 in Figures 8 and 8A. The machine may, however, have eight such stations or feeds, in which instance, it is to be imagined that the four stations or feeds shown at 1, 2, 3 and 4 are duplicated. Or any other appropriate number of knitting stations or feeds, preferably though not necessarily in multiples of four, may be provided. In any event, the machine of this example includes, as will be seen in Figure 5, a combined needle and jack cylinder 5 in the tricks or grooves 6 of which are arranged spaced pairs of plain, i. e. cylinder, knitting needles 7, and intervening pairs of pelerine instruments 8 and 9. The two pelerine instruments 8 and 9 of each pair—with left-hand and right-hand loop-spreading formations 8a and 9a

respectively are arranged side by side in the same trick or groove 6. The dial 10 is furnished with spaced pairs of rib, i. e. dial, knitting needles 11 arranged in alternating relation with the cylinder needles 7 suchwise as to enable the machine to produce 2 x 2 rib knitted fabric. For controlling the operation both of the cylinder needles 7 and of the pairs of pelerine instruments 8 and 9, there are provided in the needle tricks or grooves 6 jacks 12 furnished with butts 13 for action on the lower ends of the said needles and instruments. As will be seen from a comparison of Figures 5 and 6, the cylinder needles 7 are formed with long operating butts 14 and the pelerine instruments with short operating butts 15. The lower portions 12a of the jacks are of a springy nature and are formed with butts 16. For determining selective actuation of the jacks 12, according to patterning requirements, there are provided, in front of the spring portions 12a thereof, selectors 17 in the form of pressers which, as depicted in Figure 5, are fulcrumed at 18 and formed with butts 19 at respectively different heights. These butts 19 are adapted to be acted upon, in advance of a knitting station or feed such as that indicated at 1 in Figure 8, or in advance of each of a plurality of such stations or feeds, as the case may be, a bank of intermediate cam levers 20 which are selectively manipulated by selector bits 21 arranged in tricks in a rotary device 22 and having butts 23 at different heights according to the selection to be effected. In this specific example the drum 22 with its selector bits 21 and the associated bank of intermediate cam levers 20 together constitute a selector unit U provided immediately in advance of a knitting station or feed, such as 1, for selecting desired ones of the cylinder needles 7 to tuck at two or more succeeding knitting stations or feeds, such, for instance, as those numbered 1 and 2, as will be hereinafter described.

In advance of the selector unit U, there is provided as shown in Figure 8, a cam 24 having on its underside a downwardly inclined surface 24a for action on further butts 25 on the jacks 12 for the purpose of depressing all of the latter to a common low level 26 preparatory to selection or re-selection of the same by the said unit. The upper edge 24b of the cam 24 is adapted for action both on the long and the short butts 14 and 15 of the needles 7 and the pairs of pelerine instruments 8 and 9 respectively. Next to the cam 24, which is also adapted to function as a transfer cam for the pelerine instruments, as will be hereinafter described, is a tucking cam 27 of a thickness less than that of the cam 24 so that it will miss the short butts 15 and act on the long butts 14 only, thereby initially raising all of the needles to tucking height 28 (Figures 8 and 8A) and enabling the pelerine instruments 8 and 9 to be lowered by engagement of their short butts 15 with a downwardly inclined edge 29a of a thicker depressing cam 29 combined with the tucking cam 27 so that the pelerine instruments 8 and 9 are rendered inoperative with their tips disposed at the level 30. Next to the combined tucking and depressing cams 27 and 29 at the knitting station or feed 1 there is provided a fulcrumed clearing cam 31 adapted, whenever there is to be a division of the needles 7 so that some tuck and the remainder clear and knit at this station or feed, to be rendered inoperative by being turned down and held in the horizontal position shown in full lines. At the knitting station or feed 1, there is, of course, also provided a stitch cam 32

and an associated guard cam 33. At each of the remaining three knitting stations or feeds 2, 3 and 4 shown in Figures 8 and 8A there is provided a tucking cam 34, a movable clearing cam 31, a stitch cam 32 and a guard cam 33. For the purpose of carrying out one specific cycle of knitting, the clearing cam 31 at the knitting station or feed 2 is, like the corresponding cam at the station or feed 1, maintained in a horizontal, i. e. inoperative, position, whilst the two clearing cams at the remaining two knitting stations or feeds 3 and 4 are in their raised, i. e. operative, positions so that at the last mentioned stations or feeds, all of the cylinder needles 7 will be caused to clear and knit. It is to be clearly understood, however, that by selective manipulation of the clearing cams 31, the cycle can be varied from time to time, according to patterning requirements.

As will accordingly be appreciated, the purpose of the selector unit U is to ensure that of all the jacks 12 lowered by the cam 24 desired ones of the needle-actuating jacks (and incidentally all of the pelerine actuating jacks) shall remain down, thereby selecting the corresponding needles to tuck by permitting them to remain at tucking height 23, and enabling the butts 16 of the remaining needle-actuating jacks to be acted upon by a jack raising cam 35 with the result that the corresponding needles are raised to clearing height 36 and thereupon caused to knit by the stitch cam 32 at the station or feed 1. In this respect, it is those cylinder needles corresponding to jacks 12 the lower sprung portions 12a of which are pressed in by selectively actuated selectors 17 which are selected to tuck; the sprung portions 12a of the remaining needle-actuating jacks are allowed by the selector U to remain out so that their lower butts 16 are engaged by the jack raising cam 35. At the knitting station or feed 1 there is also provided in the jack cam box, beneath the relevant clearing cam 31, a depressing cam 37 for engagement with the butts 25 of all of those jacks which are pressed in by the action of the selector unit U for the purpose of further lowering these jacks to a low position 38 and thereby moving chamfered projections 39 formed on the said jacks beneath their butts 25 behind an upstanding undercut rib 40a on a retaining cam 40 (see Figure 5). In this way the jacks corresponding to those cylinder needles selected to tuck as aforesaid are retained in the low position 38 until they are eventually raised again, after the cam 24, by engagement of their butts 25 and 16 with lifting cams 41 and 41a provided between the knitting stations or feeds 3 and 4. In fact, the lifting cams 41 and 41a are employed for raising the retained jacks 12 preparatory to their re-selection by the unit U.

At the second station or feed 2, there is provided a further jack raising cam 42. Hence, the conditions obtaining at station or feed 1, are duplicated at station or feed 2 in so far that at both the cylinder needles selected at the selector unit U are caused to tuck and so accumulate tuck loops, whilst the cylinder needles not so selected clear and knit. The sprung lower portions of the jacks corresponding to the pairs of pelerine instruments 8 and 9 are also pressed into the cylinder 5 by the unit U so that these jacks are not affected by the jack raising cams 35 and 42.

In advance of the appropriate knitting station or feed, such as that numbered 3, there is provided, as shown in Figure 8A, a selector unit U¹,

similar in form and operation to the unit U, this further selector unit working in conjunction with a jack raising cam 43 to effect selection of desired pairs of pelerine instruments and raise the pelerine instruments slightly to the level 44 (Figure 8A) suchwise as to cause them to collect pelerine loops, that is to say, in this example, to engage, spread and retain bights or loops of yarn extending between rib knitted loops on relevant pairs of dial needles.

According to the number of knitting stations or feeds involved, it is possible to provide a selector unit U¹ in advance of each of a plurality of successive stations or feeds, such, for instance, as the stations or feeds 3 and 4, or even 2, 3 and 4, so that the selected pairs of pelerine instruments collect or accumulate a corresponding number of bights or loops at succeeding courses. In any event, at a transfer cam, such as 24, following a knitting station or stations in advance of which, or each of which, is provided a selector unit U¹, all of the pairs of pelerine instruments 8 and 9 are raised to dispose their tips at the height 45 (Figure 8) as a consequence of which the pairs of pelerine instruments, previously selected by the unit or units U¹ to collect pelerine bights or loops, are caused to effect transference of such expanded bights or loops to appropriate pairs of dial needles 11.

Thus, assuming for simplicity's sake that the set outs shown in the two Figures 8 and 8A are combined to provide the cam system and selecting means of a four-feed machine, then one specific cycle of knitting in accordance with this invention may be as follows:

At each of the first and second knitting stations or feeds 1 and 2, both cylinder and dial needles knit, selected cylinder needles being, 40 however, caused to tuck. Then at the third knitting station or feed 3, the selected cylinder needles knit off the accumulated tuck loops, and selected pelerine instruments are caused to engage and laterally spread bights or loops of yarn 45 extending between rib loops on relevant dial needles. Finally, the previously selected pelerine instruments are operated by the cam 24 at the transfer station, to effect transference of the expanded bights or loops to appropriate dial needles preparatory to such bights or loops being knocked over to form pelerine stitches.

But, as previously described herein, by adding to the number of knitting stations or feeds, appropriately disposing selector units U and U¹ 55 where required, and effecting suitable manipulation of the movable clearing cams 31 all manner of accumulations of tuck loops and collections of pelerine bights or loops can be made at desired locations.

60 The cylinder and dial needles may, of course, alternately be set out to produce a broad rib fabric, and the interspersion of the pairs of pelerine instruments with the cylinder needles is by no means limited to the set out illustrated 65 in Figures 8 and 8A.

In a further modification, instead of the cylinder needles and the pairs of pelerine instruments being formed with long and short operating butts, they may be provided with butts in 70 respectively different planes for engagement in separate cam tracks.

What we claim is:

1. Knitted fabric having at desired locations thereof small openings produced by the incorporation in the fabric of pelerine stitches, and

tuck loops which are so linked with the said pelerine stitches that at the aforesaid locations the surface of the fabric is raised.

2. Knitted fabric having at desired locations thereof pelerine stitches, and tuck loops which are so directly interlinked with said pelerine stitches as to produce raised eyelet effects.

3. Knitted fabric having at desired locations thereof eyelets produced by incorporation in the fabric of pelerine stitches, and tuck loops which are so linked with opposite sides of the said pelerine stitches as to open out the eyelets laterally and frame them with raised puckered effects.

4. Knitted fabric having at each of desired locations thereof a pelerine stitch, and at least one tuck loop which is so linked with one side only of the said pelerine stitch as to produce a raised eyelet effect.

5. Double-sided knitted fabric comprising a structure of knitted loops of which some are drawn to one face and others to the opposite face of the fabric, the latter having at desired locations thereof pelerine stitches produced by spreading bights of yarn extending between knitted loops facing in one direction and interlooping the spread bights with the said loops, and tuck loops which are linked with the pelerine stitches suchwise as to provide raised eyelet effects at the aforesaid locations.

6. Single-sided knitting fabric consisting of a structure of knitted loops all drawn to one face only of the fabric, and wherein at desired locations of the latter there are provided raised eyelet effects comprising, in combination, pelerine stitches produced by spreading bights of yarn extending between and interlooping the spread bights with appropriate knitted loops, and tuck loops which are linked with the pelerine stitches.

7. A double-sided knitted fabric having both inwardly facing and outwardly facing knitted loops and wherein at desired locations thereof there are provided raised eyelet patterning effects comprising, in combination, pelerine stitches produced by spreading bights of yarn extending between and interlooping the spread bights with inwardly facing knitted loops, and tuck loops which are associated with outwardly facing knitted loops and are linked with the said pelerine stitches.

8. Rib knitted fabric having spaced panels each consisting of a plurality of consecutive wales of inwardly facing knitted loops and intervening panels each consisting of a plurality of consecutive wales of outwardly facing knitted loops, the said fabric incorporating, at selected points, linked tuck-pelerine stitches comprising, in combination, pelerine stitches produced by laterally spreading bights of yarn extending between and interlooping the spread bights with adjacent inwardly facing knitted loops, and tuck loops produced in wales of outwardly facing knitted loops, the said tuck loops being linked with sides of the pelerine stitches.

9. Knitted fabric comprising a basic structure of knitted loops and having non-patterned areas of the said basic loop structure interspersed with pre-arranged areas patterned at desired locations thereof by the incorporation of linked tuck-pelerine stitches providing raised eyelet effects, the said stitches comprising, in combination, pelerine stitches produced by spreading bights of yarn extending between and interlooping the spread bights with appropriate knitted

loops, and tuck loops which are linked with the pelerine stitches.

10. The method of producing a knitted fabric incorporating raised eyelet effects comprising the steps of drawing a course of loops selected ones of which are held without being knitted whilst the remainder are so knitted, at a subsequent course of knitting clearing and knocking-over the held loops and drawing through the same knitted loops in the said subsequent course so as to produce tuck stitches, at the last mentioned course also collecting and thereafter laterally spreading bights of yarn extending between knitted loops in the course, and, at a still further course of knitting, causing the spread bights to be interlooped with adjacent knitted loops suchwise as to produce pelerine stitches with which the tuck stitches are linked.

11. The method of producing a knitted fabric patterned by the incorporation therein at desired locations of raised eyelet effects, comprising the steps of drawing successive courses of loops selected ones of which are held without being knitted whilst the remainder are so knitted, at the succeeding course of knitting clearing and knocking-over the accumulation of held loops and drawing through the same knitted loops in the said succeeding course suchwise as to produce tuck loops, in the last mentioned course and subsequent courses collecting bights of yarn extending between knitted loops in these courses, laterally spreading these bights, and, at a still further course of knitting, causing the spread bights to be interlooped with adjacent knitted loops suchwise as to produce pelerine stitches with which the tuck stitches are linked.

12. The method of knitting a ribbed fabric comprising the steps of reversely drawing loops in successive courses so as to produce spaced panels each of at least two adjacent wales of inwardly facing rib knitted loops and intervening panels each of at least two adjacent wales of outwardly facing plain knitted loops, selected loops in the outwardly facing wales of a plurality of the successive courses being held without being knitted, at the next succeeding course clearing and knocking-over the accumulation of held loops and drawing through the same plain knitted loops in the said next succeeding course suchwise as to produce tuck loops, in the last mentioned and subsequent courses collecting bights of yarn extending between adjacent rib loops in the inwardly facing wales, laterally spreading these bights, and, at a still further course, causing the spread bights to be interlooped with adjacent rib knitted loops so as to produce pelerine stitches with which the tuck loops are linked to provide raised eyelet patterning effects.

13. The method of making knitted fabric on a knitting machine equipped with needles and pelerine instruments and having at least two knitting stations, including the steps of causing selected needles to tuck and thereby hold loops without knitting them at at least one knitting station, at at least one further knitting station clearing and casting the held loops off the selected needles to produce tuck loops and also causing selected pelerine instruments to engage and spread bights of yarn extending between loops on relevant needles, and, at a non-knitting station, transferring the spread bights to adjoining needles.

14. The method of making knitted fabric on a multi-feed knitting machine equipped with

11

needles and pre-arranged pelerine instruments, including the steps of causing selected needles to tuck and thereby hold loops without knitting them at a plurality of succeeding feeds, at the next feed clearing and casting the accumulation of held loops off the selected needles to produce tuck loops, also at the last mentioned feed and at least one further succeeding feed, causing selected pelerine instruments to engage and spread bights of yarn extending between loops on 10 relevant needles, and, at a non-knitting station, transferring the collections of spread bights to adjoining needles.

15. Knitted ware comprising non-patterned areas of a basic loop structure, and, interspersed with said non-patterned areas, areas patterned by the incorporation therein at selected locations of pelerine stitches and tuck loops which are so

linked with the said pelerine stitches as to produce in the fabric small openings surrounded by raised puckered effects.

ALFRED PERCY SAUNDERS.
HENRY HAROLD HOLMES.
